UNITED STATES PATENT OFFICE.

ROBERT B. PATTERSON, OF WASHINGTON, DISTRICT OF COLUMBIA.

CIRCUIT-CONTROLLING DEVICE.

No. 918,086.

Specification of Letters Patent.

Patented April 13, 1909.

Application filed July 3, 1906. Serial No. 324,600.

To all whom it may concern:

Be it known that I, ROBERT B. PATTERSON, a citizen of the United States, residing at Washington, in the District of Columbia, have invented certain new and useful Improvements in Circuit-Controlling Devices, of which the following is a specification.

This invention is a circuit-controlling device which is capable of establishing or interrupting, or of establishing and interrupting an electric circuit, preferably at predetermined times.

In its preferred embodiment the device comprises a clock mechanism, adjustable contacts adapted to be closed by a device operated by said clock mechanism, and electro-magnetic means controlled through said clock-operated contacts and serving to establish or interrupt the electric circuit.

Means are also provided whereby the circuit through the said electro-magnetic means is broken after such impulse has been imparted as is sufficient either for the establishment or the interruption of the main circuit.

The circuit-controlling device is adapted, among other uses, for controlling arc lamp circuits, and in such use may conveniently be inserted in a lamp-supporting pole or standard and arranged in circuit with such number of lamps as it may be desired to light or extinguish at one time. The apparatus is designed particularly for such use, and while capable of controlling circuits carrying relatively heavy currents, it may be of small size and adapted in exterior dimensions for insertion in standard types of poles; it is moreover simple in construction, capable of minute adjustment as to the time of establishing or interrupting the circuit, is not liable to derangement owing to changes of temperature or other causes, and does not require skilled labor for its maintenance or adjustment.

For a full understanding of my invention reference is made to the accompanying drawings, wherein—

Figure 1 is a front elevation of a preferred form of circuit-controlling device, the cover of the switch-casing being removed, and the circuit connections omitted; Fig. 2 is a diagrammatic view showing the circuit connections; Fig. 3 is a sectional view of a device for interrupting the electromagnetic circuit at predetermined intervals and for predetermined times; Fig. 4 is a face view of the

same partly broken away; and Fig. 5 is a detail view of one form of device for controlling the electromagnetic circuit.

Referring to the figures, 1 represents a casing adapted for insertion in a standard pole, the exterior dimensions of the casing preferably not exceeding $4\frac{1}{2}$ by 4 by 12 inches; 2 represents the face of a rotatable clock dial the clock train being suitably incased and being preferably adapted to give one revolution of the dial in each twenty-four hours; this dial 2 is rotatable with a pinion 3 shown in dotted lines in Fig. 1, said pinion having double the number of teeth of the usual twelve-hour pinion 4 of the clock train. In the form illustrated the dial 2 is of metal, and is divided into hour periods and convenient subdivisions thereof, the subdivisions indicated being fifteen-minute periods. The clock dial may be shaded or colored in part to indicate the "night" hours.

5 and 6 represent conductive arms, the angular position of which is adjustable at will, the arms being adapted to be clamped together and to the dial 2 by means of a milled clamping nut 7. The arm 5 is adapted at each revolution to engage a spring contact 8 secured to the casing as shown at 9, said spring contact being included in the electro-magnetic circuit as hereinafter described. The arms 5 and 6, being in electrical contact with the dial 2, are also included in said circuit. The arm 6 is shown as somewhat longer than the arm 5 and is adapted at each revolution to engage a spring contact 10, shown in dotted lines in Fig. 1. The spring contacts 8 and 10 are suitably insulated from each other.

In its preferred form each of the arms 5, 6 is turned outwardly at its end as shown at 11, and to the inner face of this outwardly turned portion is secured with interposed insulation a metal strip having an upturned end 12 which projects beyond the outer face of the arm, in line with a portion 13 of the latter which is radial with respect to the dial 2. The purpose of this arrangement is to secure accuracy in time of contact as follows: The portion 13 of each arm being set to register with any of the radial lines on the face of the dial 2 as may be desired, the spring contact will be first engaged by the insulated strip 12 and will be pressed outwardly thereby, without, however, closing the circuit; as the strip 12 passes beyond the end of the spring the

latter will strike the upturned end of the arm and thereby close the electromagnetic circuit at a time corresponding accurately to the desired time of contact for which the arm is set.

5 14, 15 represent two superposed solenoids, shown as of the iron-clad type, having a common vertically movable core 16, the end sections of the core being of iron and its central section 17 of brass or other nonmagnetic material.

10 18, 19 are the terminals of the supply circuit, and 20, 21 the terminals of the load circuit, the terminals 18, 20 and 19, 21, respectively, being adapted to be spanned by

15 bridges 22, 23 shown as of the laminated copper type. These bridges are carried by curved arms 24, 25, pivotally mounted upon the casing 1 at 26 and 27, respectively. These arms are connected by a toggle lever

20 28, the toggle pin 29 passing through a slot 30 in a lower extension 31 of the core 16. A spring 32 extends between the arms 24, 25 and serves to assist the break on the upward movement of the core and to retain the parts 25 in the open position during such time as the main circuit is interrupted.

30 33, 34 represent fixed terminals adapted to be bridged by a spring contact 35 pivotally mounted on the terminal 33, as most clearly shown in Fig. 5. In the upper position of the core 16 this contact is closed by the action of a spring 36, but on its downward movement the lower insulated end 37 of the extension 31 depresses a bent portion 38 of the contact 35 35 and interrupts the circuit, the circuit being broken so long as the core remains in its lower position, that is to say, so long as the switch is closed.

35 The operation of the device as above described will be readily understood by reference to the diagrammatic circuit connections shown in Fig. 2. 39 represents a source of direct or alternating current connected to the terminals 18, 19 respectively; the terminal

40 18 is also in direct electrical connection with the moving arms 5, 6 through the dial 2. The contact 8 serves for closing the switch and is connected through lead 40, contacts 33 and 34, and the upper solenoid 14, with 45 the supply terminal 19. Contact 10 serves for opening the switch and is directly connected through the lower solenoid 15 with the load terminal 21. In both figures the mechanism is shown in full lines in the "on" 50 position, the arm 6 progressing toward the contact 10, upon reaching which the main circuit will be opened through the switch. It will be noted that no current traverses either solenoid in either position of the switch.

55 60 When the arm 6 reaches the contact 10 the electromagnetic circuit will be closed through the lower solenoid 15 and the bridge 23, and the consequent upward movement of the core will open the main circuit, there- 65 by interrupting the electromagnetic circuit

at the bridge 23. The switch will remain open until the arm 5 is brought again into contact with the spring 8, whereupon the electromagnetic circuit will be closed through lead 40, contacts 33, 34 and the upper solenoid 14; the downward movement of the core will then close the switch by extending the toggle lever 28; by said downward movement the bent portion 38 of the contact 35 is depressed, thereby breaking the circuit of the solenoid 14 at this point. It will be noted that in the case of either solenoid the closing of the switch-operating circuit is momentary, and does not endure for the full period required for the arms 5 or 6 to pass the contacts 8 or 10.

70 It is often desirable to provide supplemental arms, corresponding in form to 5 and 6, respectively, but set at convenient intervals, say one hour, after said arms 5 and 6, 75 the purpose of these supplemental arms being to insure the opening or closing of the switch in case the first contact should fail to operate for any reason, as, for instance, because of an interruption of the current at the 80 particular time when the arms were traversing the contacts. It will be further understood that any number of arms corresponding in form to arms 5 and 6 may be supplied, and set as desired with relation to the dial, 85 thereby opening and closing the circuit as many times and at such intervals as may be desirable.

90 In addition to serving as a guide for the core the slot 30 serves in opening the switch 100 to permit a certain free movement of the core before the end of the slot strikes the toggle pin 29, whereby a definite blow is delivered upon the latter and the operation is rendered more certain.

105 It will be understood that the circuit through the solenoids may be closed by hand or by means other than the clock movement, and such closing may be effected at a central station or other point remote from the switch; and my invention is not restricted to the use of a clock movement for controlling the switch. It will be further understood that even when control is effected by a clock movement the clock may be situated 110 at a point remote from the switch, and that one clock may control any desired number of switches. When the clock is placed in the lamp standard as above described I prefer to mount in proximity thereto a heating device, usually consisting of an incandescent lamp, the circuit of which is controlled by a thermostat adapted to close the same when the temperature falls to such low point as might interfere with the operation of the 115 clock: such device forms no part of my present invention and need not be further described herein.

120 In the use of the switch for controlling illuminated sign circuits and certain power 125

circuits, it is sometimes desirable that the switch-controlling circuit should be definitely interrupted for predetermined periods, as, for instance, on Sunday of each week. I have illustrated a simple mechanism for effecting this result, the position of the same being indicated in Fig. 1 and the mechanism illustrated in detail in Figs. 3, 4. This mechanism comprises a wheel 41 having seven or other desired number of teeth and secured to a bushing 42 which is rotatable on an arbor 43 projecting outwardly from a fixed plate 44 in the rear of the rotary dial 2; this wheel is adapted to be moved 15 through one-seventh of its circumference by an insulated pin 45 carried by the dial 2 at each complete revolution of the latter. The bushing 42 carries also conductive disks 46, 47 upon the periphery of which bear respectively spring contacts or brushes 48, 49, the brush 48 having a rearward extension 50 making electrical contact with the rear face of the dial 2. The contact 49 is electrically connected with a binding post 51 secured to 25 the plate 44. The conductive disk 46 has a nonconductive section 53 extending over one-seventh of its circumference. This device is in use interposed in the electromagnetic circuit, preferably between the terminal 18 and the dial 2; as indicated in dotted lines at 52 in Fig. 2. It will be obvious that the electromagnetic circuit will be normally established through this device so long as the brush 48 bears upon the conductive 35 portion of the periphery of disk 46, but is definitely interrupted whenever the brush bears upon the nonconductive portion or covering of the disk, that is to say, in the construction shown for one-seventh of the 40 total time. During such time engagement of the arms 5 or 6 with the contacts 8 or 10 does not operate the switch.

I claim:

1. A circuit controlling device comprising 45 two solenoids each provided with a core, a main switch comprising two oppositely disposed pairs of fixed contacts, bridge pieces for said contacts, toggle mechanism between said pairs of contacts for simultaneously 50 operating said bridge pieces, connections whereby the toggle mechanism is actuated by the movement of the cores of said solenoids, and means whereby the movement of the core 55 interrupts the circuit of the actuating solenoid.

2. A circuit controlling device comprising two aligned solenoids each provided with a core, a non-magnetic section, between said cores, a main switch comprising two oppositely disposed pairs of fixed contacts, bridge pieces for said contacts, toggle mechanism between said pairs of contacts for simultaneously operating said bridge pieces, connections whereby the toggle mechanism is actuated by the movement of 60

the cores of said solenoids, and means whereby the movement of the core interrupts the circuit of the actuating solenoid.

3. A circuit controlling device comprising two solenoids each provided with a core, a 70 main switch comprising two oppositely disposed pairs of contacts, bridge pieces for said contacts, toggle mechanism for simultaneously operating said bridge pieces, said toggle mechanism comprising pivoted arms 75 attached to said bridge pieces and toggle levers connecting said arms, connections whereby the toggle mechanism is actuated by the movement of the cores of said solenoids, and means whereby the movement of 80 the core interrupts the circuit of the actuating solenoid.

4. A circuit controlling device comprising two solenoids each provided with a core, a main switch comprising two oppositely disposed pairs of contacts, bridge pieces for said contacts, toggle mechanism for simultaneously operating said bridge pieces, said toggle mechanism comprising pivoted arms 85 attached to said bridge pieces, toggle levers connecting said arms and a spring extending between said arms, connections whereby the toggle mechanism is actuated by the movement of the cores of said solenoids, and means whereby the movement of the core 90 interrupts the circuit of the actuating solenoid.

5. A circuit controlling device comprising two solenoids each provided with a core, a main switch comprising two oppositely disposed pairs of fixed contacts, bridge pieces for said contacts, toggle mechanism between 100 said pairs of contacts for simultaneously operating said bridge pieces, connections whereby the toggle mechanism is actuated 105 by the movement of the cores of said solenoids, and means whereby the movement of the core interrupts the circuit of the actuating solenoid, said means comprising a pair of terminals and a movable bridge piece 110 adapted to span said terminals, said bridge piece actuated by the movement of said core.

6. A circuit controlling device comprising two solenoids each provided with a core, a main switch comprising two oppositely disposed pairs of fixed contacts, bridge pieces for said contacts, toggle mechanism between said pairs of contacts for simultaneously operating said bridge pieces, connections whereby the toggle mechanism is actuated 115 by the movement of the cores of said solenoids, and means whereby the movement of the core interrupts the circuit of the actuating solenoid, said means comprising a pair of fixed terminals and a bridge piece pivotally 120 mounted on one of said terminals and adapted to span said terminals, said bridge piece actuated by the movement of said core.

7. A circuit controlling device comprising 130

two solenoids each provided with a core, a main switch comprising two oppositely disposed pairs of fixed contacts, bridge pieces for said contacts, toggle mechanism between 5 said pairs of contacts for simultaneously operating said bridge pieces, connections whereby the toggle mechanism is actuated by the movement of the cores of said solenoids, and means whereby the movement of 10 the core interrupts the circuit of the actuating solenoid, said means comprising a pair

of fixed terminals, and a spring-controlled bridge piece pivotally mounted on one of said terminals and adapted to span said terminals, said bridge piece actuated by the 15 movement of said core.

In testimony whereof, I affix my signature in presence of two witnesses.
